METHOD OF IGNITING ORGANIC FUELS

Johann Gunther Cohn, East Orange, N. J., assignor to Baker & Co., Inc., Newark, N. J., a corporation of New Jersey

Application December 19, 1947, Serial No. 792,673

2 Claims. (Cl. 219—32)

1

This invention deals with fuel igniters and is concerned in particular with a method of igniting fuels in molecular or other state of fine subdivision, such for example as inflammable gases or "atomized" liquid fuels.

Gas igniters, as such, are, of course, known and have been used in a variety of appliances and for a variety of purposes. The direct flame of a pilot light is in almost universal use in domestic appliances. Electrical igniters, such as high intensity electrical sparks and incandescent electric resistance wires have also been used in some types of appliances.

All such igniters—pilot light, electrical spark, incandescent wire—rely on the principle of induced ignition by means of a heating element at a temperature at least equal to the ignition temperature of the fuel under the particular conditions involved, the fuel-air mixture being heated locally to such a temperature that the heat generated is sufficiently large to propagate flame ignition in the particular mixture. Such igniters suffer from a number of shortcomings. Pilot flames especially are expensive in use, unreliable and dangerous. Electrical sparks and incandescent wires are preferable to the pilot light in many respects but are quite expensive and for this reason unsuitable for most frequent applications. Thus, for instance, in the case of electrical resistance igniters, in order to insure ignition independently of voltage fluctuations, it is necessary to operate such resistors at a temperature substantially in excess of the minimum temperature at which ignition occurs. This severely shortens the life of such resistors since at such temperature the metal of the wire is subject to recrystallization, grain growth and softening. To avoid such an excessive temperature one may have to use a voltage stabilizer which makes the appliance too expensive for most uses. Furthermore, the operation of such igniters is quite expensive due to the very high power consumption.

Experiments have been made to ignite gases by means of catalytic igniters, i. e. by means of catalysts of platinum or the like, the ignition of the gas being based on the catalytic combustion of the inflammable gas. In practice, however, such experimental catalytic igniters have been found wanting, due to unreliability of operation and difficulties in initiating or maintaining the catalytic reaction and, particularly, in accelerating the catalytic combustion to a point where the flameless combustion of the catalytic reaction ignites the gaseous fuel.

2

In some cases, the initiation of the reaction and the acceleration thereof to ultimate ignition is easier than in other cases. For instance in the case of manufactured or so-called "city" gas, such catalytic reaction is relatively easy due to the presence in such gas of free hydrogen, the catalytic combustion of free hydrogen being easily initiated leading to the ignition of the organic fuel. In the case of natural gas which consists mainly of methane with minor other components and also in the case of commercial gases, such as, methane, propane, butane, ethane, etc., not containing free hydrogen, ignition through catalytic combustion of the organic fuel is extremely difficult and the commercial catalytic igniters do not operate at all with such gases. Under all conditions, catalytic igniters, as heretofore proposed, are very erratic and moreover show a substantial time lag between the start of the catalytic reaction and the ignition.

It is, therefore, one object of this invention to provide a simple igniter for finely divided fuels which shall be used for a variety of applications. It is another object to provide such igniters for hydrocarbons, such as, for instance, propane, butane, etc. free from uncombined hydrogen. It is still another object of this invention to provide an igniter which shall lead to the combustion of such fuels by a combination of electrically as well as catalytically generated heat, irrespective of whether or not such fuel contains free hydrogen. It is still another object of this invention to provide an igniter as described which shall be simple and sufficiently inexpensive to permit its installation and reliable use in industrial as well as domestic appliances. Other objects and advantages of my invention will appear in the description hereinafter following.

From the research of the United States Bureau of Mines (Technical Paper 375 by P. G. Guest "Ignition of Natural Gas-Air Mixtures by Heated Surfaces"), it appears that though one might have supposed that catalytic action, tending to accelerate the combustion of the gases, would result in lower ignition temperatures, or rather that ignition would occur through a catalytically heated surface maintained at a lower temperature, it was found that the temperature of the catalytic material must be higher for ignition of the natural gas than the temperature of non-catalytic materials, e. g. as much as 300° C. higher for the catalytically active platinum than for the catalytically inactive nickel; so that for all practical purposes a noncatalytic material

would furnish a better igniter than catalytic metal.

The difficulty of catalytic ignition in general and especially of organic fuels lies in the fact that the catalytic combustion begins as a relatively slow reaction on the catalyst surface and that the acceleration to the point of ignition of the fuel is subject to interference by side reactions or by the production of reaction products. The catalytic ignition starts with a reaction of relatively slow speed and which is completely confined to the catalytic surface. The slowly generated reaction heat raises the temperature of the catalyst surface and of the adjacent gas layer, thus continuously increasing the speed of the catalytic reaction and also inducing the thermal reaction in the adjacent gas layer until eventually enough reactive particles or "chain carriers" are created to cause ignition of the gas. This process is, however, inhibited by the formation during the reaction of non-inflammable reaction products and also by the consumption of the available oxygen in the neighborhood of the catalyst. Furthermore, the ultimate ignition is interfered with in part by rapid loss, by conduction, of the heat of the reaction by the catalyst, so that an insufficient amount of heat energy is available to ignite the gas.

In catalytic igniters as heretofore described, the results obtained are, therefore, highly irregular and contradictory due to the overheating necessary to overcome inhibiting effects. Thus there is no particular advantage in the use of a catalytic wire over an incandescent wire and, furthermore, the cost of a catalytic wire able to resist the overheating is such that such catalytic wire becomes entirely impractical and, since the catalytic function is not used, would in the final analysis be an incandescent resistance heater rather than a catalytic element. Thus, e. g. in the Bureau of Mines paper referred to, it is stated that, as a matter of practical fact, it is quite difficult to ignite natural gas without fusing the catalytic platinum wire, due to the accompanying overheating.

I have found that it is nevertheless possible, notwithstanding the conclusions reached by earlier researchers, to provide a catalytic igniter for inflammable gases and other fuels such as kerosene and the like in finely divided state, in a fuel-air mixture which is highly practical and which is, in fact, far superior to any igniter heretofore developed and which is, thus, adapted to ignite not only synthetic or manufactured gas (so-called "city" gas) containing free hydrogen, but also natural gas, saturated hydrocarbons such as methane, butane, propane and so forth and other finely divided fuels, irrespective of the presence or absence of free hydrogen.

The structural features of the igniter for igniting such fuels according to my invention are illustrated in the accompanying drawings, forming part hereof, and in which:

Figure 1 represents a diagram of an ignition system embodying the igniter,

Figure 2 represents an elevational view of one embodiment of the igniter, and

Figures 3 and 4 represent diagrammatic views of two other embodiments of the igniter.

Figure 1 illustrates a system of ignition, involving a gas burner 1 with flash-back port 2 and flash-back tube 3 and an electrically heated igniter 4 of catalyst metal, e. g. platinum, in the form of a coil. The igniter may be used in the horizontal position, as shown, or in a vertical or any inclined position. The igniter coil 4 is

more specifically shown in Figure 2 as consisting of a helically coiled wire in a circuit 5 and 5' and power supply 6. In Figure 3, the catalytic igniter 4 is shown in the form of a helically coiled wire with decreasing coil diameter and increasing coil pitch, and in Figure 4, the catalytic igniter is shown in the form of a plurality, in this case two, helically coiled platinum wires 4' and 4'', coil 4' having a larger coil diameter than coil 4'' and surrounding coil 4'' along part thereof, each coil being adapted to be electrically heated in the circuit 5 and 5' and 5'' respectively.

The igniter coil 4, as well as the coil 4' and 4'', is provided with a plurality of turns of such number as may be desired. The number of turns of the coil depends somewhat on the fuel to be ignited, the number increasing with the difficulty of igniting the fuel involved. For gases not containing free hydrogen, the number of turns should, preferably, be at least six for such gases as butane and propane and at least twelve for a gas such as methane. The coil diameter and the spacing of the turns should be such as to provide a compact coil unit with large catalyst surface in a relatively small space. For this reason, the coil spacing should be as close as possible, the turns being spaced apart just sufficiently to avoid short-circuiting. The coil diameter is somewhat variable, being, however, preferably, of the order of from about 1 to 5 mm., the preferred diameter being about 2 to 4 mm.

The wire itself may consist of a single strand or a plurality of strands. The catalyst metal, of which the wire is formed, is normally platinum or an alloy thereof with other suitable metal or metals, such as metal of the platinum group, e. g. rhodium or iridium, or other precious metal, or suitable base metal, e. g. nickel. The catalyst material may also be other metals of the platinum group and alloys thereof. If desired, such catalyst material may also be in sintered form, and in such form may contain in finely divided condition refractory oxide, such as oxide of thorium, beryllium, and so forth. As far as alloys of platinum are concerned, they will normally contain a major amount of platinum and a minor amount of alloying metal, e. g. in the form of such alloys as 90% platinum with 10% rhodium or iridium, and so forth.

The critical factor in the construction of the igniter is the diameter of the wire of the coil, correlated to a small electrical power input. This diameter must not exceed a maximum of about .003" and, while not falling below about .001", should preferably be of the order of about .0015" to .0025". In the case of stranded wire, the sum total of the diameters of the individual strands must be such as to yield cross-sections within the limits stated. The power input to the catalyst wire is very small, up to the order of about 2 watts, but in any case not more than that which would raise the temperature of the coil to a temperature below the recrystallization temperature of the catalyst material, i. e. the temperature at which recrystallization and grain growth occur and sagging of the wire takes place due to serious softening, such as 600° C. for platinum.

Taking, for instance, a catalyst wire of platinum with a diameter of 0.002" in the form of a helical coil, in accordance with the embodiment of Figure 2, with six turns, with a coil diameter of 2 mm., the wattage input is approximately 0.5 watt for the ignition of propane, compared with a customary input of 30 watts for ignition of the incandescent electrical resistance type. The same igniter, Figure 2, when used for ignition of "city"

gas containing free hydrogen requires an input of about 0.8 watt.

The igniter may be in the form of a straight coil, as illustrated in Figure 2, or it may be in the form of a tapered coil, as in Figure 3. It may have a uniform pitch or a varying or variable pitch. There may be one coil, as in Figures 2 and 3, or there may be a plurality of coils as in Figure 4. With respect to such igniters of coils of different structural, and catalyst, phases, reference is made to my copending application of even date, Serial Number 792,674 dealing with such heterophase catalyst igniters, such igniters being of particular usefulness for the ignition of methane and the like.

Insofar as the use of the igniters in appliances, etc. is concerned, any suitable system may be employed. Figure 1 is intended to illustrate the use of the igniter of this invention in the conventional flash-back system. Any other applicable system may, of course, be employed.

The operation of the igniter according to this invention is as follows. The igniter is maintained, by way of the electrical heating, at a relatively low temperature, e. g. approximately 300° C. in the case of propane, butane and the like or approximately 450° C. in the case of methane, which is more difficult to ignite than the other gases mentioned, and is brought in contact with the gas or other fuel to be ignited which will customarily be by way of playing a stream of the fuel, mixed with air, on the igniter. A flameless combustion of the fuel ensues and, in the manner described above, the temperature is raised continuously until ignition occurs. The time interval between the first contact of the fuel with the igniter and its actual ignition is of the order of one second or fraction thereof, so that to the observer such ignition appears to occur instantaneously. Upon completion of the ignition, the igniter is withdrawn from the fuel or the fuel is withdrawn from the igniter, as by means of installing the igniter in a flash-back system. The withdrawal may also be accomplished by directing a horizontal stream of gas to the igniter, the flame of the ignited gas thereupon rising and thus removing itself from contact with the igniter.

The electrical heating of the catalytic igniter may be either continuous or controlled to coincide with the opening of the fuel jet, as may be desired.

The effective operation of the igniter of this invention has been quite surprising. It shows a very great advantage over the usual catalytic igniter in that the ignition occurs with such rapidity that no detrimental overheating of the wire takes place. In contrast to the resistance heaters the igniter herein described has to be heated electrically only to a very moderate temperature, far below such temperature at which recrystallization, grain growth or softening take place. This is possible because the electrically generated heat is not used to actually induce the ignition but only helps in starting the catalytic reaction. Subsequently, the catalytic process generates the heat leading to the ignition of the fuel. It is thus not necessary, in the case of igniters according to this invention, to heat the igniter to the ignition temperature or even beyond such ignition temperature. It may be noted, also, that if a platinum coil, as used in the embodiment of the igniter of this invention, is heated by external means, rather than by elec-

trical means, ignition of hydrocarbons does not occur in the manner described in the instant case, but that such coil has to be heated close to the ignition temperature of the fuel before ignition occurs.

The small diameter wire of the igniter of the invention is adapted to heat up rapidly with the progress of the catalytic reaction to the peak temperature prevailing upon ignition of the fuel, 10 but the time at which the catalyst is at such peak temperature is only a small fraction of the ignition time. Recrystallization and grain growth and softening are substantially avoided during such short time interval.

15 The igniter may be used for the ignition of inflammable gases, including saturated hydrocarbon gases not containing free hydrogen. It may also be used for the ignition of finely divided other fuels, such as "atomized" fuel oils, kerosene, 20 etc., i. e. organic fuels in finely divided state in a fuel-air mixture, wherever the fuel in such finely divided state is capable of being oxidized in the presence of the catalyst.

25 The igniter may be used in domestic and industrial appliances, such as stoves, furnaces, and so forth. The source of electrical power may be the line supply, with an interposed resistor or with a suitable transformer, or a battery, as may be desired. The igniter may also be used in instruments or other devices, e. g. in cigarette lighters in conjunction with a small storage or "dry" battery, or in conjunction with a transformer fed by the line supply, in which case it is 30 not necessary to use special "lighter fluids" but possible to use any handy organic fuel, such as gasoline.

35 What I claim is:

1. A method of automatically igniting an 40 organic fuel in finely divided state capable of being catalytically oxidized in a flowing fuel-air mixture in the presence of a catalyst, comprising contacting said fuel-air mixture with an electrically heated helical closely spaced coil of catalyst metal taken from the group of metals of 45 the platinum group and alloys thereof, the wire of said coil having a diameter of from 0.001" to about 0.003", electrically heating said coil during 50 said contact to a temperature substantially below the ignition temperature of said fuel in said fuel-air mixture and below the recrystallization temperature of said catalyst metal, thereby oxidizing said fuel and raising the temperature in the neighborhood of said coil to the temperature 55 at which ignition of said fuel in said fuel-air mixture occurs, and automatically terminating the contact between said coil and said ignited fuel.

2. A method of automatically igniting an 60 organic fuel in finely divided state capable of being catalytically oxidized in a fuel-air mixture in the presence of a catalyst, comprising contacting said fuel-air mixture with an electrically heated helical closely spaced coil of platinum or alloy 65 thereof, the wire of said coil having a diameter of from 0.001" to about 0.003", electrically heating said coil during said contact to a temperature substantially below the ignition temperature of said fuel in said fuel-air mixture and below the recrystallization temperature of said catalyst metal, thereby oxidizing said fuel and raising the temperature in the neighborhood of said coil to the temperature at which ignition of said fuel 70 in said fuel-air mixture occurs, and automatically 75 in said fuel-air mixture occurs, and automatically

terminating the contact between said coil and
said ignited fuel.
